[57] CLAIM

The ornamental design for an equipment bag or similar article, as shown and described.

DESCRIPTION

FIG. 1 is a perspective view taken from the top; one end and one side of an equipment bag or similar article showing our new design with a pocket flap in an open position;

FIG. 2 is an elevational view taken from the end shown in FIG. 1, the opposite end being a mirror image of the end shown;

FIG. 3 is an elevational view taken from the side opposite that shown in FIG. 1; and

FIG. 4 is a bottom plan view thereof.
